FLUSH TANK SUPPLY MECHANISM

William H. Schulte, Trenton, N. J.

Application August 4, 1931, Serial No. 555,009

4 Claims. (Cl. 137—68)

This invention relates to flush tanks and more especially to an improved water supply control for such tanks.

One object of the invention is to provide a float operated valve mechanism which will operate quietly, be efficient in operation, and cheap in manufacture.

A further object is to provide a water supply control of the type secured to the tank bottom which will secure aeration of the water supply.

In the accompanying drawing, forming a part of this specification, there is shown, by way of illustration, a construction embodying the invention, which will now be described in detail and the features forming the invention then pointed out in the claims.

In the drawing:

Figure 1 is a transverse section through a flush tank showing my water supply control in side elevation;

Figure 2 is an enlarged side elevation of the water supply control with parts broken away to show its construction;

Figure 3 is an enlarged section with the valve partly open or partly closed as the case may be;

Figure 4 is a view similar to Figure 3 with the valve in full open position; and

Figure 5 is a section on line 5—5 of Figure 1.

Referring to the drawing, 10 designates an ordinary flush tank within which operates my water supply control, denoted generally as 11, the valve of which is operated through suitable mechanism by the usual float 12.

The body member 13 of my water supply control is flanged at 14 and provided with a downwardly extending screw threaded shank 15 which passes through a hole in the bottom of tank 10 and is secured thereon by a nut 16 cooperating with flange 14 to clamp the body member 13 in position on the tank 10, the usual water main connection (not shown) being secured on threaded shank 15 below the nut 16. Within the body 13 is formed a flange 17 which may be shaped to form the valve seat, but preferably I provide a valve seat 1 separate therefrom and cushioned thereon by a fibroid or other washer 2 as shown. This construction is desirable as the valve seat is readily accessible for repair or substitution and the closing movement of the valve well cushioned.

Above the internal valve seat flange 17 the body member 13 is internally threaded to receive the externally threaded lower end of a tube or valve casing 18 provided with an annular row of ports 3 for supply of water to the tank 10. The upper end of the casing 18 is externally threaded to re-

ceive a bracket 19 provided with a pair of spaced upstanding lugs 20 through which passes a pivot pin 21 on which is pivoted a lever 22 to the outer end of which is secured a ball arm 23 for the float or ball 12. To the inner end of lever 22 is secured a valve stem 24, preferably by pivot 25, which carries at its lower end a valve member denoted generally as 26, secured thereon by a pivot pin 27.

The lower end of the valve member 26 is formed to provide a supply valve 4 cooperating with valve seat 1, this valve being smaller in radius than the tube or valve casing 18 so that the water may flow upward thereabout when the supply valve 4 has been raised from its seat by the dropping of the float 12. Above the supply valve 4 and separated therefrom by a reduced neck 5 is a plunger 6 of such size as to neatly fit the tube or valve chamber 18, the lower end of this plunger being so spaced above the supply valve 4 as to secure closure of the annular row of ports 3 by its lower edge in the closed position of the supply valve 4.

Usually the supply water would pass directly to the tank 10 through the annular row of ports 3, but I provide means for its aeration in its passage to the tank 10. For this purpose the upper end 25 of the body member 13 is internally recessed to provide a space outside the valve chamber 18. Within this recess is secured, as by threading 7, an aeration tube 8 which extends upwardly about the valve chamber 18 and forms therewith a passage 9 for delivery of the supply water to the top of the tank 10. At its upper end the aeration tube 8 is provided with a fitting 28 suitably secured thereto, as by brazing, provided with a plurality of inwardly extending lugs 29, contacting with the valve chamber tube 18 to maintain the aeration tube 8 in properly spaced relation thereto. Bracket 19 is preferably provided with a downwardly extending flange 30, spaced from and extending well below the upper end of the aeration tube 8 to provide a suitable spray head operating to break up the water flow for aeration thereof and direct the supply water downwardly into the tank 10.

In general, the lowering and rising of the float operate the valve member 26 to fill the tank 10 and, when properly filled, shut off the further supply of water thereto. In order to prevent chattering or whistling of the supply valve in its closing movement, as the supply valve 4 approaches its seat to shut off the supply water, the guide plunger and auxiliary valve 6 is simultaneously decreasing the effective area of the annular row of ports 3.

What I claim is:—

1. In a float operated supply secured to a tank bottom, the combination with the supply control valve of a pipe receiving the supply water from 5 said valve and extending above the maximum water level in the tank, and a spray head above the maximum water level in the tank receiving the supply water from said pipe for spraying the supply water into said tank above the maximum water level in the tank, whereby the supply water always passes into said tank above the water level therein and aeration of the supply water secured.
- 10 2. In a float operated supply secured to a tank bottom, the combination of a valve casing extending upwardly above the maximum water level in the tank and having lateral discharge ports, a pipe 15 enclosing said valve casing and having its open upper end located above the maximum water level in the tank, and a spray head carried by the upper end of the valve chamber above the maximum water level in the tank receiving the supply water from the open upper end of said pipe for spraying the supply water into said tank, whereby 20 the supply water always passes into said tank above the water level therein and aeration of the supply water secured.
- 25 3. In a float operated supply secured to a tank bottom, the combination with a valve casing having lateral discharge ports near the bottom of the tank, and a float valve controlling said ports, of a pipe enclosing the valve casing and extending 5 above the maximum water level in the tank, and a spray head above the maximum water level in the tank receiving the supply water from said pipe for spraying the supply water into said tank, whereby the supply water always passes into said 10 tank above the water level therein and aeration of the supply water secured.
4. In a float operated supply secured to a tank bottom, the combination of a valve casing extending upwardly above the maximum water level in 15 the tank and having lateral discharge ports near the bottom of the tank, a float valve controlling said ports and closing the valve casing above the ports, a pipe enclosing the valve casing and extending above the maximum water level in the 20 tank, and a spray head above the maximum water level in the tank receiving the supply water from said pipe for spraying the supply water into said tank, whereby the supply water always passes into said tank above the water level therein and 25 aeration of the supply water secured.
